UNITED STATES PATENT OFFICE.

HARRY T. KRAKAU, OF CLEVELAND, OHIO, ASSIGNOR TO THE NATIONAL MALLEABLE
CASTINGS COMPANY, OF CLEVELAND, OHIO.

CAR-COUPING.

1,122,952.

Specification of Letters Patent. Patented Dec. 29, 1914.

Application filed April 21, 1913. Serial No. 762,446.

To all whom it may concern:

Be it known that I, HARRY T. KRAKAU, a citizen of the United States, residing at Cleveland, Cuyahoga county, Ohio, have invented new and useful Improvements in Car-Couplers, of which the following is a specification, reference being had to the accompanying drawings, in which—

Figure 1 is a partial section of a coupler showing my improvements applied thereto; Fig. 2 is a section on lines II—II of Fig. 1; and Fig. 3 is a detail of the lock lifter.

My invention relates to car couplers and is designed to provide means whereby the lock is positively held in locked position, regardless of the shocks and jars to which the coupler is subjected.

Referring to the drawings, A indicates the coupler-head, B the lock, and C the lock cavity.

The lock lifter is comprised of a lower member 2 and an upper member 3. The lower member 2 has a link 4 by which it is connected with a hook or eye 5 in the head 25 of the lock B. The two members are joined together by a loose pivot 6, which allows a limited vertical movement of the upper member 3 relative to the lower member 2. The upper member 3 has an enlargement 7 intermediate its ends, which is adapted to 30 lie within a correspondingly shaped top hole 8 of the lock cavity, and substantially fills this hole (as is shown in Fig. 2), so as to exclude dirt, moisture, etc., which would interfere with the operation of the coupler. The enlargement 7 is shaped so as to slide 35 freely in the hole 8 so that if desired the device may be used with a lock of wedge type. In the upper end of the member 3 is an eye 9 by which the member 3 is engaged with the uncoupling mechanism. The inclined rear face 10 of the member 2 bears against the rear wall 11 of the lock cavity when the parts are in locked position, while immediately above the wall 11 is an undercut shoulder or stop 12, against which the correspondingly inclined upper end 13 of the member 2 will normally strike when pushed upwardly by the creeping of the lock. The 50 surface 13, by its rising into contact with the stop 12, will normally prevent the lock from creeping, but a jar or blow might dislodge the member 2, so that it will clear the stop 12, and the lock would then be free to 55 jump upward and clear the knuckle-tail.

To prevent such accidental dislodgment of the member 2 a shoulder 14 on the lower member 2 is provided, which engages a projection 15 on the upper member 3. The bearing of the shoulder 14 against the projection 15 makes it impossible for the member 2 to swing forwardly out of the line of engagement with the stop 12 unless a lifting force is applied to the eye 9 of the member 3, the first effect of which is to pull the lower member into a vertical position out of the path of the stop 12. A further lifting will raise the lifter and the lock into position shown in dotted lines in Fig. 1. It will be seen, therefore, that when the lock is in 70 locked position in the coupler-head and the upper and lower members 2 and 3 of the lock-lifter are in their usual positions (as shown in full lines in Fig. 1), the lower member 2 is in position to engage the stop 75 12 and cannot be dislodged therefrom by a shock or jar, because the engagement of the shoulder 14 and the projection 15 prevents any angular movement of these two members except when the member 3 is actuated from 80 above.

Various changes may be made in the mechanism which I have shown and described herein without departing from my invention, since

What I claim is:

1. In a car coupler, a head having a top hole, a vertically movable lock, a lock lifter comprised of two members, one of said members being pivotally connected to the lock 90 and extending upwardly therefrom, the second member having a pin and slot connection with the first-named member and extending upwardly through the hole in the head, a stop on the head, a surface on the 95 first-named member coöperating with said stop for locking-the-lock, and means for preventing the said surface from being thrown out of the path of the stop when the lock is in locked position, comprising a bearing on each of the two members.

2. In a car coupler, a coupler-head having a top hole, a vertically movable lock, a lock-lifting member pivoted to the lock and free to tip rearwardly into locking engagement 105 with the head, a link having a pin and slot connection with the lock-lifting member and extending upwardly through the top hole, and coöperating bearings on the lock-lifting member and the link to prevent angular 110

movement therebetween when the parts are in locked position.

3. In a car coupler, a coupler-head having a top hole, a vertically movable lock, a lock-lifting member pivoted to the lock and free to tip rearwardly into locking engagement with the head, a link having a pin and slot connection with the lock-lifting member and extending upwardly through the top

hole, and means for preventing the lock 10 lifting member from tipping forwardly out of engagement with the head, comprising a shoulder on the lock-lifting member and a projection on the link.

HARRY T. KRAKAU.
